UNITED STATES PATENT OFFICE.

EMORY LEON CHAFFEE, OF BELMONT, MASSACHUSETTS, ASSIGNOR TO JOHN HAYS HAMMOND, JR., OF GLOUCESTER, MASSACHUSETTS.

VACUUM TUBE.

Application filed October 14, 1918, Serial No. 257,993. Renewed February 27, 1925.

Some of the objects of the present invention are to provide in a radio receiving system improved means for reducing the disturbing effects of interference, or static in such a manner that large variations of potential caused by large or intense signals will produce no greater effect upon a telephone or other similar or suitable receiving instrument than would be produced by a comparatively weak signal; to provide an improved detector; and to provide other improvements as will appear hereinafter.

In the accompanying drawings, Fig. 1 represents a diagrammatic side elevation of one form of a receiving system constructed in accordance with the present invention; Fig. 2 represents a sectional elevation of one form of detector embodying the present invention; Fig. 3 represents a side elevation of the detector; Fig. 4 represents a detail of a grid used in the detector; Fig. 5 represents a section on line 5—5 of Fig. 2; Fig. 6 represents a plate current curve of a detector plotted in conjunction with a grid current curve; Figs. 7 and 8 represent respectively characteristics of the ideal curve of sensitiveness of a detector of the bulb type; Figs. 9 and 10 represent curves plotted for different variations in the grid potential.

Referring to the drawings, one form of radio receiving system is shown in Fig. 1 wherein an open aerial circuit including an antenna 10, primary coil 11 and ground 12 is illustrated as coupled with a closed oscillatory circuit 13 including a secondary coil 14 and a variable condenser 15. One side of the condenser 15 is connected by a lead 16 to a grid 17 of a detector 18 while the opposite side of the condenser 15 is connected by a lead 20 through a potentiometer 21 and a suitable resistance 22 to a filament 23 of the detector 18. This filament 23 is maintained heated by a battery 24 controlled by a rheostat 25. The detector 18 is arranged to control a receiving circuit 30, the terminal leads 31 and 32 of which are respectively joined to the filament 23 and the plate electrode 33. The circuit 30 includes a high potential bat-

tery 34 and a telephone receiver 35 or any other suitable receiving instrument.

For the purpose of reducing the effect of intense signals upon the receiving circuit a form of detector is employed, preferably of the gaseous type, comprising a bulb 36 of lime glass or any other suitable composition mounted in a base 37 such as a brass cylindrical member filled with insulation 38 through which the lead wires pass to the grid 17, filament 23 and the plate electrode 33. In the form of detector here shown, the plate electrode 33 consists of a nickel cylinder suspended within the bulb 36 by means of suitable wires 40 fixed to a glass arm support 41 formed as a part of the bulb proper. The cylindrical plate electrode 33 encircles the grid structure which is here formed as an elongated coil 42 the convolutions of which are connected at a plurality of points by interwoven wire strands 43 arranged parallel to the longitudinal axis of the coil. The grid coil 17 is suspended by a wire 44 from the support 41 and encircles the filament 23, but is out of contact therewith. This detector, when pumped to a certain pressure indicated by the appearance of the discharge from the induction coil, such as a green fluorescence on the lime glass walls of the bulb and a trace of blue in the center of the bulb, acts to reduce the effect of intense signals and limits the possible variations of the plate or output current. In order to provide a detector bulb or tube which will give the desired results the particular characteristic curve which the detector should have is decided upon and then the tube or bulb constructed and pumped to give the required curve. It may then be operated at the proper point on the curve for the achievement of the desired result.

In order that this use of a characteristic curve may be clear, reference is made to Fig. 6 of the drawings where a curve 50 represents a typical plate current curve which might be possessed by a detector constructed in accordance with the invention and which is plotted against volts on the grid as abscissas. A

curve 51 represents the corresponding grid current curve plotted to a current scale representing smaller currents than the scale for the plate current. It is well known that if the potential of the grid varies by a small increment V , both plus and minus about a constant polarizing potential A , the plate current will suffer an average increase because the curvature of the plate curve is such about the point A that a greater increase than decrease in plate current is produced, when the potential varies by the same amount on either side of A . On the other hand, a variation of potential of the grid about the point B will produce an aggregate decrease in plate current. A curve S can then be plotted, the ordinate of which will represent the change in plate current caused by a certain variation of grid potential about the polarizing potential represented by the distance of the ordinate from the zero axis of volts. If the ordinate of sensitiveness is plotted upward it means that the plate current increases and if plotted in a negative direction the current decreases. At the points of maximum increase or decrease the maximum change of plate current occurs, which means that the device used as a detector has its maximum sensitiveness. If a large potential variation of the grid occurs a greater change in plate current obtains, which is proportional to the area under the sensitiveness curve bounded by the limits of potential variation. It is evident, therefore, that a variation of potential above the point C will give no response. Should, however, the grid 17 be polarized to the potential represented by the point A , then any variation of potential of maximum amplitude less than A will give a signal or response proportional to the area under the curve bounded by the two limits of potential on either side of A . It is apparent that the area does not increase in proportion to the increase in voltage, so that a loud or intense signal does not give a response proportional to its intensity but the response is less in proportion the more intense the signal.

If the potential variation exceeds the value A , the area representing the response will extend over into the negative part of the S curve and this area must be subtracted from the positive area. Thus a potential variation greater than A will actually produce a less response than a small potential variation as given by A .

In Fig. 7 a form of sensitiveness curve of an ideal bulb is shown, wherein a potential variation about A reaching on either side of A to the points B and C will give the maximum variation of plate current obtainable and any variation of potential greater or less than that will give less response. In Fig. 8 another form of ideal sensitiveness curve is shown.

In the practical operation of a detector, the above ideal conditions may be approximated, for example, by introducing a certain amount of gas, such as air at a pressure of 10^{-1} of a millimeter into the evacuated bulb 70 and designing the grid accordingly. Thus in Fig. 9 a typical sensitiveness curve is one plotted in accordance with one form of detector and closely approximates the ideal curve of Fig. 6 except that the curve is not sufficiently compressed in the direction of grid volts, that is, the range of grid volts B C which the variation in the potential of the message should have to give the best protection against interference is greater than the potential of most radio signals. To overcome this difficulty the radio oscillations of the incoming signal may be amplified and then applied to this protecting detector. 85

Another method of obtaining nearly an ideal protective characteristic for a vacuum detector is by the introduction of a gas so that a small kink 52 is produced in the plate current curve as shown in Fig. 10 and the resulting curve of sensitiveness S , when plotted, resembles the ideal form of characteristic shown in Fig. 8.

Although I have only disclosed one form in which this invention is embodied, it is to be understood that the invention is not limited to any particular construction but might be embodied in various forms without departing from the spirit of the invention or the scope of the appended claims. 100

Having thus described my invention, I claim and desire to protect by Letters Patent of the United States:

1. In a detector, an evacuated bulb, a tubular plate electrode supported within said bulb, a grid comprising a plurality of convolutions of wire arranged in superposed relation and connected together by a twisted strand wire, said grid being supported within said electrode out of contact therewith and a filament cooperating with said grid. 105

2. In a detector, an evacuated bulb, a tubular plate electrode supported within said bulb, a grid comprising a plurality of convolutions of wire arranged in superposed relation and connected together by a twisted strand wire arranged in parallel relation to the longitudinal axis of said convolutions, said convolutions passing between the pairs of strands, said grid being supported within said plate electrode out of contact therewith and a filament arranged to cooperate with said grid. 115

3. A vacuum tube grid comprising a coil of conducting material and twisted strand reinforcing elements extending longitudinally of the coil. 125

4. A three electrode vacuum tube including a grid comprising a coil of conducting wire and twisted strand reinforcing wires ar- 130

ranged longitudinally of the coil and spaced substantially equal distances, by passing peripherally of the coil. ¹⁰

5. A three electrode vacuum tube including a grid comprising a coil of conducting wire and interwoven two stranded reinforcing wires arranged longitudinally of the coil and connected with the convolutions of the coil to maintain them spaced apart by substantially equal distances, by passing said convolutions between the two interwoven strands composing the reinforcing wires.

Signed at New York, in the county of New York and State of New York, this 24th day of September, A. D. 1918.

EMORY LEON CHAFFEE.
